UNITED STATES PATENT OFFICE.

NAPOLEON DU BRUL, OF CINCINNATI, OHIO.

DESIGN FOR A CIGAR-WRAPPER-CUTTING PLATEN.

SPECIFICATION forming part of Design No. 35,522, dated December 31, 1901.

Application filed May 29, 1901. Serial No. 62,442. Term of patent 14 years.

To all whom it may concern:

Be it known that I, NAPOLEON DU BRUL, a citizen of the United States, and a resident of Cincinnati, in the county of Hamilton and State of Ohio, have invented and produced a new and original Design for Cigar-Wrapper-Cutting Platens, of which the following is a full, clear, and exact specification, reference being had to the accompanying drawings, forming part of this specification, in which—

Figures 1 and 2 are views showing opposite sides of the cutting-platen.

As shown in the drawings, the leading or material features of my design are, first, a substantially rectangular plate; second, a group of perforations therein restricted to an area that is approximately oval or shaped like a cigar-wrapper with the major axis of the area lying at an angle to the front edge of the plate, so that it extends from near the front edge rearwardly and laterally in an approximately diagonal direction; third, a solid

imperforate narrow path extending around and conforming to the outline of the area named; fourth, an outer narrow oval or cigar-wrapper-shaped line of perforations extending around and conforming to the solid imperforate path, and, fifth, a solid imperforate area extending from said narrow oval or cigar-wrapper-shaped line of perforations to the edges of the rectangular plate.

Having thus described my design, what I claim as new therein, and desire to secure by Letters Patent, is—

The design for a cigar-wrapper-cutting platen, substantially as herein shown and described.

The foregoing specification signed this 18th day of May, 1901.

NAPOLEON DU BRUL.

In presence of—

KATHERINE E. MANNING,
EDWIN S. CLARKSON.
